H. J. SHELTON

GRINDER AND SHREDDER

Filed Nov. 1, 1922

Fig. 2.

INVENTOR

Harry J. Shelton.

BY *Henry Kinealy*
ATTORNEY

UNITED STATES PATENT OFFICE.

HARRY J. SHELTON, OF ST. LOUIS, MISSOURI.

GRINDER AND SHREDDER.

Application filed November 1, 1922. Serial No. 598,356.

To all whom it may concern:

Be it known that I, HARRY J. SHELTON, residing in the city of St. Louis, in the State of Missouri, have invented a new and useful

- 5 Improvement in Grinders and Shredders, of which the following is a full, clear, and exact specification, reference being had to the accompanying drawings, which form a part thereof.
- 10 My invention relates to grinders and shredders and more particularly to grinders and shredders wherein the material to be ground is, to a certain extent, drawn or blown into the machine by a current of air 15 induced by a suction fan and is drawn or blown, in the same manner, from the housing of the machine after it has been ground.

In using such a machine if one material is ground and then it is desired to grind a material to a different degree of fineness it is necessary to change the perforated plate forming the lower circumferential wall of the grinding chamber so as to provide a surface having either smaller or larger openings, as the case may be, through which material is passed when ground.

Heretofore grinders and shredders have been made with the housing thereof formed with an upper and lower section, one lower 30 edge of the upper section being hinged to the corresponding upper edge of the lower section so that the upper section might be swung away from the lower section to expose the grinding chamber of the machine. 35 To gain access in this way to the grinding chamber in a grinder and shredder and to change the perforated plate therein, was a long and tedious task since a feed pipe connecting with a bin was usually attached to the intake opening of the grinder and this pipe had to be removed or partially removed when the upper section of the grinder and shredder was swung back as described above. In addition it was difficult to remove 40 the perforated plate even after access to the grinding chamber had been obtained.

The objects of my invention are to provide a grinder and shredder constructed so that the perforated plate forming the lower 45 wall of the grinding chamber therein may

be quickly and easily removed and replaced without disturbing the feeding device for said grinder and shredder; to provide a grinder and shredder which may be formed as a unit and need not be divided into upper 55 and lower sections; to provide a partially removable cage for holding the perforated plate forming the lower wall of the grinding chamber; and to provide means whereby said cage and said perforated plate may 60 be easily rendered accessible.

My invention is fully shown in the accompanying drawings wherein similar letters are used to designate similar parts. Fig. 1 is a plan view, in section, of a grinder and 65 shredder embodying my invention; and Fig. 2 is a partial side view along the lines 2-2 in Fig. 1.

Referring to the figures the grinder has the housing A, comprising the side walls E, 70 only shown in part in the drawings, which are held together by the tie rods E'; a back wall, preferably formed by the plate F; and a front wall G. The housing A has the grinding chamber B therein with the hammers C mounted on and adapted to be rotated by the shaft D journaled in the side walls E as shown in Fig. 1. The grinding chamber has the upper circumferential wall T, only partially shown, which terminates 80 at its front end in a bar N' attached thereto and which, preferably, extends between the side walls E of the housing. A grinding plate K, only partially shown, is preferably mounted so as to cover a part of the inside surface of the wall T, all as shown in Fig. 2. The lower circumferential wall of the grinding chamber B is formed by the perforated plate H which is removably mounted in the substantially semi-circular cage J. One end of the cage J, preferably the rear end, is provided with the lugs L so that the cage may be swingably mounted on the rod M, as shown in Fig. 2. The other end of the cage J is provided with the 85 flange N which is adapted to be held in contact with and secured to the bar N' by the bolts O or any other suitable means, preferably, arranged so as to be loosened or tightened from the outside of the housing. The 90 95 100

lower edge of the front wall G is inserted in the recesses P formed near the lower edges of the side walls E and the upper end of the wall G is normally held in place by the wedge 5 R which fits in the slots Q. The slots Q are, preferably, formed in lugs Q' extending from the side walls E, as shown in Fig. 1. The ribs S positioned on the side walls of the housing and arranged to follow the contour 10 of the lower circumferential wall of the grinding chamber are provided to make a close joint between the side walls E and the plate H when in operative position.

When it is desired to substitute for the 15 perforated plate H a plate having different size perforations therein the wedge R is removed from the slots Q, thereby allowing the front wall G to be swung outwardly at the top, as shown in Fig. 2, and then be removed by lifting the lower end thereof out 20 of the recesses P. The bolts O which normally hold the cage in place at the lower side of the grinding chamber are removed and the cage J is swung into the position shown 25 by the dotted lines in Fig. 2. The perforated plate H may then be quickly and easily removed and a new plate substituted therefor. When the substitution has been completed the cage is raised so that the flange N engages 30 with the bar N' and the bolts O are inserted in place. When the cage J is lowered any load which is in the machine is dumped into the lower part of the housing thus rendering it easier to move the perforated plate H, as described. When the bolts 35 O have been put in place and tightened, the lower edge of the front wall G is inserted in the recesses P, then swung into place and the wedge R is hammered down into the 40 slots Q.

I do not propose to limit my invention to the specific details of construction shown in the drawings since it may be readily seen that the method of normally holding the 45 cage J in place, the method of retaining the front wall G in place, and the form of the various parts, may be varied within wide limits without deviating from the spirit of my invention.

50 What I claim as new and desire to secure by Letters Patent is:

1. A grinder and shredder comprising a housing having a grinding chamber with revolvable hammers mounted therein, a cage 55 hingedly supported at its rear end, a perforated plate removably mounted in said cage to form the lower circumferential wall of said grinding chamber, and means for detachably securing the front end of said cage 60 to the upper circumferential wall of said housing whereby said plate is maintained in operative position.

2. A grinder and shredder comprising a housing having a grinding chamber with revolvable hammers mounted therein, a cage 65

hingedly supported at its rear end, a perforated plate removably mounted in said cage to form the lower circumferential wall of said grinding chamber, the front end of said cage having a flange thereon, a bar extending between the side walls of said housing at the front end of said grinding chamber, means for detachably securing said flange to said bar whereby said plate is maintained in operative position, and the front 75 wall of said housing being constructed and arranged to be removed from said housing without disarranging the other parts thereof.

3. A grinder and shredder comprising a 80 housing having a grinding chamber with revolvable hammers mounted therein, a cage hingedly supported at the rear end of said grinding chamber, a perforated plate removably mounted in said cage to form the lower circumferential wall of said grinding chamber, the front end of said cage having a flange thereon, a bar extending between the side walls of said housing at the front end of said grinding chamber, means for detachably securing said flange to said bar whereby said plate is maintained in operative position, a rib provided on the inner surface of each of the side walls of said grinding chamber and arranged to follow the contour of 85 said plate when said plate is in operative position, and the front wall of said housing being constructed and arranged so that it may be removed therefrom.

4. In a grinder and shredder of the class described, the combination of a housing having a grinding chamber with revolvable hammers mounted therein, a cage hingedly mounted on said housing at its rear end, a perforated plate removably mounted in said cage to form the lower circumferential wall of said grinding chamber, means whereby the front end of said cage is detachably secured to hold said plate in operative position, and the front wall of said housing adjacent the front end of the said cage being constructed and arranged so that it may be removed from said housing without disarranging the other parts thereof, whereby when the front end of said cage is detached and moved into inoperative position said plate may be removed therefrom through the opening left by the removal of said front wall.

5. In a grinder and shredder of the class described, the combination of a housing having a grinding chamber with revolvable hammers mounted therein, a cage hingedly mounted on said housing at its rear end, a perforated plate removably mounted in said cage to form the lower circumferential wall of said grinding chamber, the front end of said cage having a flange arranged thereon, a bar extending between the side walls of said housing at the front end of the upper 120

circumferential wall of said grinding chamber, means which may be loosened from the outside of said housing for detachably securing said flange to said bar to hold said

and arranged so that the portion thereof below said bar may be removed from said housing without disarranging the other 10 parts thereof.

5 cage and said plate in operative position, and the front wall of said housing adjacent the front end of said cage being constructed

In witness whereof I have signed my name to this specification.

HARRY J. SHELTON.
